Inventor

Hugh P. Eanes
By Remond S. Hadley
his Attorney

UNITED STATES PATENT OFFICE.

HUGH P. EANES, OF ASHEVILLE, NORTH CAROLINA, ASSIGNOR TO PARAMOUNT MACHINE COMPANY, A CORPORATION OF NORTH CAROLINA.

RACK FOR HOLDING WARP THREADS.

Original application filed August 2, 1924, Serial No. 729,666. Divided and this application filed August 2, 1924. Serial No. 729,769.

This is a division of my co-pending application, Serial No. 729766, filed August 2, 1924.

My invention relates to an improvement in racks for holding warp threads.

The object is to provide means for holding these threads in position in two tiers while they are being operated upon by the tying-in machine, and while the threads of the upper and lower tiers are being tied together.

In the accompanying drawings:—

Fig. 1 is a plan view;

Fig. 2 is an enlarged detail;

Fig. 3 is a transverse section on the line 3—3 of Fig. 1, looking in the direction of the arrow.

Brackets 1, 2, 3 and 4 project laterally in opposite directions from the bed 5 of the machine. The warp threads of the spent spools are combed over the rods 9 across the bed of the machine, and fastened and wound tight upon the inner roller 6 at the right-hand side of the machine, and a cylindrical separating-bar 7 extending inwardly from the arms 8 is then placed over the warp threads, and is forced downwardly to depress the threads slightly and held by wing-nuts 13. The warp threads to be tied are then combed over in the same way, and their ends drawn around the outer roller 6 to give the required tension thereto, and both rollers 6 have ordinary card covering thereon, making them take hold of the threads. The bar 7, as shown in Fig. 3, compresses the two tiers of warp threads, thus formed, making space for the entrance therebetween of the tongue of the selector of the tying-in machine (not shown).

Sleeved upon each rod 9 is a spiral spring 14 between the coils of which the warp threads are passed and held. The required tension is given the springs 14 through a sleeve 15 slidably mounted on each rod, as shown in Fig. 2, and these sleeves are slideable in the frame as well as on the rods, and

are held in place with the required degree of pressure against the spiral springs to cause them to hold the warp threads by any approved means such as the buttons 16 held 50 adjustable on the rods by the set-screws 17.

When the tied warp threads are to be removed, it is simply necessary to unscrew the set-screws 17 and loosen the buttons 16, whereupon the springs 14 themselves will expand, push the sleeves 15 forward, and release the threads.

In this way a very quick, simple means is provided for fastening the threads while being selected and tied. 60

I claim:

1. A device of the character described including a support, a rod held thereby, a spiral spring sleeved over said rod and adapted to receive threads drawn over the 65 rod between its coils, a sleeve mounted on the rod and adapted to be moved longitudinally thereof for adjusting the tension of the spring, and means for holding said sleeve in its adjusted position. 70

2. A device of the character described including a support, rods, spiral springs thereon adapted to receive threads drawn over the rods between their coils, a sleeve mounted on each rod and adapted to be slid to 75 force the coils of the springs tightly against the threads, and adjustable means for locking the sleeves with the required degree of pressure against the springs.

3. A device of the character described including a support, a rod held thereby, a spiral spring sleeved over said rod and adapted to receive threads drawn over the rod between its coils, a sleeve mounted on the rod and adapted to be moved longitudinally thereof for adjusting the tension of the spring, means for holding said sleeve in its adjusted position, an adjustable bar for separating the rows of threads, and means for holding said bar in its adjusted position. 85 90

In testimony whereof I affix my signature.
HUGH P. EANES.
